BRUSH HOLDER

Benjamin H. Bernick, Davenport, Iowa

Application November 28, 1934, Serial No. 755,145

6 Claims. (Cl. 15—146)

The present invention relates to means for holding a plurality of paint brushes in operative relation so that the user thereof may cover a greater amount of surface in a given time. Among the objects of this invention are to provide an improved apparatus for the purpose indicated; to provide apparatus which is inexpensive to manufacture and easy to assemble; to provide apparatus of the character indicated which may be used either with or without a handle; and such further objects, advantages, and capabilities as will hereafter appear and as are inherent in the construction disclosed herein. My invention further resides in the combination, construction, and arrangement of parts illustrated in the accompanying drawings and, while I have shown therein what is considered the preferred embodiment of this construction, I desire the same to be understood as illustrative only and not to be interpreted in a limiting sense.

In the drawings annexed hereto and forming a part hereof,

Fig. 1 is an elevational view of one form of my apparatus with four paint brushes shown in dotted lines;

Fig. 2 is a fragmentary view taken in the direction indicated by the arrows on the line 2—2, Fig. 1;

Fig. 3 is a transverse sectional view taken substantially along the plane indicated by the line 3—3, Fig. 1;

Fig. 4 is a transverse sectional view taken substantially along the plane indicated by the lines 4—4, Figs. 1 and 2;

Fig. 5 is a fragmentary plan view illustrating the use of a particular clamping means;

Fig. 6 is a transverse sectional view taken substantially along the plane indicated by the line 6—6, Fig. 5;

Fig. 7 is an elevational view of another form of my construction arranged to hold brushes in an inclined position;

Fig. 8 is a plan view of the structure shown in Fig. 7;

Fig. 9 is a transverse sectional view taken substantially along the plane indicated by the line 9—9, Fig. 7;

Fig. 10 is a fragmentary plan view of a modified form of holder to be used with a structure shown in Figs. 7 and 8, the same being taken substantially along the plane indicated by the line 10—10, Fig. 11;

Fig. 11 is a fragmentary elevational view of the structure shown in Fig. 10.

Reference will now be made in greater detail to the annexed drawings for a more complete description of my present invention. In the form of construction shown on Sheet 1 of the drawings, pairs of channel members 1 and 2 are assembled in nested arrangement, as shown in Fig. 3. If the number of brushes to be used does not exceed the capacity of the channel member 1, it will be unnecessary to use the second channels 2. Whether this will be necessary or not will depend upon the number of brushes used and the width thereof. In order to clamp the brush-holding channels against the brushes and thus secure them in place, U-bolts are passed around these channels and between the brushes and the nuts are tightened up, as shown in Fig. 3. The U-bolts are designated by the numeral 3 and a cross bar connecting the two ends of each bolt is designated by the numeral 4. A clamp 5 extends across the end of the assembly, as shown in Fig. 2, and the ends thereof are drawn toward the channel members by means of nuts and bolts 6. Filler blocks 7 are arranged between the clamp and the channel members so as to insure that the channels will be drawn tightly against the end brush.

This device is shown as being equipped with a handle 8, made of either wood or pipe, but this may be omitted, if desired. The handle is intended to be used when painting roofs, floors, and the like, but is ordinarily not used when painting walls. Arms 9 are shown connected to the handle 8 and as having their free ends bent laterally and engaged by the cross bars 4 which hold them and the handle securely fastened to the channel 1. A hook 10 is shown as passing through both sides of one of the channels, the same being designed to suspend the device from a ladder when the painter wishes to go down and not carry his brushes with him. The arms 9 have enlargements 11 which are connected to the handle 8 by means of the bolts 12. These arms are provided with a plurality of holes, as shown in Fig. 4, thus permitting adjustment of the angle of the handle with relation to the brushes. As indicated above, the handle may be used or dispensed with, as desired. A modified form of clamping device for clamping the channels against the brushes is illustrated in Figs. 5 and 6 in which a loop 13 is shown as being provided with a cam 14 which operates in an obvious manner.

The channels 15 and 16 (see Figs. 7 to 11) are similar to the channels 1 and 2 except that they are provided with slots 17 for the reception of

the J-bolts 18 or U-bolts 21. It is preferable to use two bolts for each brush, when using the J-bolts, so as to insure that the brushes will be held rigidly in place and will not change their angle with respect to the channels when such change is not desired. In Figs. 7 and 8, the handles of the brushes are shown as being mounted in notches 19 for the purpose of maintaining them in their adjusted positions. If desired, 10 clamping bolts 20 may be passed through the slots 17 to draw the two channels together so that there will be no relative slipping thereof.

A modified form of brush clamping means 21 for use with the channels 15 and 16 is shown in 15 Figs. 10 and 11. It is not believed that this form of construction needs any further explanation as the same appears to be obvious.

In Fig. 6, blocks of wood 22 are shown within the channel bars. These are for the purpose of 20 preventing the cam 14 from causing distortion of the bars.

Having now described my invention, I claim:

1. A paint brush holder comprising channel bars to engage a plurality of paint brushes and 25 hold them in alignment, the bars being nested with their open sides facing in the same direction, and clamping means to draw the bars into tight engagement with the brushes, the bars having their edges scalloped to grip the brushes 30 and hold them in adjustment.

2. In a paint brush holder, a pair of nested channel bars both facing in the same direction and relatively longitudinally slideable, holding means cooperating therewith to hold a plurality 35 of paint brushes tightly against the edges of

the channels, and a handle connected to the bars to enable the user to have a wider range of use than he would have without the handle.

3. In a paint brush holder, a pair of nested channel bars having scalloped edges facing in the same direction, and clamping means to hold the brushes against the scalloped edges of the bars in adjusted position. 5

4. In a brush holder, channel bars having central longitudinal slots extending through the major portion of the length thereof, the bars being nested, one within another, facing in the same direction and adjustable longitudinally with relation to each other, and U-bolts passing through the slots to secure the brushes to the 10 bars. 15

5. In a brush holder, channel bars having central longitudinal slots extending through the major portion of the length thereof, the bars being nested, one within another, facing in the same 20 direction and longitudinally slideable with relation to each other, and bolts passing through the slots to hold the bars in relatively adjusted position.

6. In a brush holder, parallel channel bars 25 facing in the same direction and having central longitudinal slots extending through the major portion of the length thereof so as to permit of adjustment of brushes longitudinally of the bars, clamping means passing through the slots 30 and adjustable therein, the bars being held against separation by said clamping means and being longitudinally adjustable with relation to each other.

BENJ. H. BERNICK. 35
